CLAIM

The ornamental design for a jewelry clasp, as shown
and described.

DESCRIPTION

FIG. 1 is an exploded perspective view of a jewelry
clasp showing my new design;

FIG. 2 is a top plan view thereof;

FIG. 3 is side elevational view thereof, the opposite side
being a mirror image;

FIG. 4 is a bottom plan view thereof; and

FIG. 5 is a left end view of the female member;

FIG. 6 is a right end view of the female member;

FIG. 7 is a left end view of the male member;

FIG. 8 is a right end view of the male member; and

FIG. 9 is a perspective view of the assembled clasp.
The broken line showing of a jewelry band in FIG. 9 is
for illustrative purposes only and forms no part of the
claimed design.

FIG. 1.

FIG. 2.

FIG. 3.

FIG. 4.

FIG. 5.

FIG. 6.

FIG. 7.

FIG. 8.

FIG. 9.
